UNITED STATES PATENT OFFICE.

CHARLIE H. POOL, OF SAVANNAH, GEORGIA.

LADDER ATTACHMENT.

1,288,182.

Specification of Letters Patent. Patented Dec. 17, 1918.

Application filed March 22, 1916, Serial No. 86,023. Renewed September 28, 1918. Serial No. 256,144.

To all whom it may concern:

Be it known that I, CHARLIE H. POOL, a citizen of the United States, residing at Savannah, in the county of Chatham and 5 State of Georgia, have invented new and useful Improvements in Ladder Attachments, of which the following is a specification.

This invention contemplates the provision 10 of a ladder attachment in the nature of a shelf adapted to project horizontally from one rung of the ladder, in combination with an adjustable supporting means for the shelf whereby the latter can be maintained in a 15 true horizontal position irrespective of the inclination at which the ladder is arranged.

The invention is very advantageous whenever use of a ladder is found necessary. The nature of the invention will be better 20 understood from the following description when taken in connection with the accompanying drawings, the invention residing in the construction, combination and arrangement of parts as claimed.

25 In the drawings forming part of this specification like numerals of reference indicate similar parts in the several views and wherein:—

Figure 1 is a front elevation of the ladder 30 showing the invention associated therewith.

Fig. 2 is a side elevation, showing two positions of the ladder.

Fig. 3 is a detail view of one of the rung 35 engaging members for the shelf.

Fig. 4 is a similar view of one of the adjustable sections of the rung engaging members disposed above the shelf.

Fig. 5 is a detail view of the slotted link 40 providing a connection between the shelf and the supporting means therefor arranged beneath the shelf.

Before entering into a detail description of what is herein shown and described, I 45 desire to have it understood that the same is merely illustrative of one embodiment of the invention to which I do not limit myself, and that such changes in the construction and arrangement of parts may be resorted to when desired as fall within the scope of 50 what is claimed.

As shown in this particular instance, the device forming the subject matter of my invention consists of a pair of identically 55 constructed rung engaging members 10, each being provided with a hook terminal 11 adapted to embrace the rung adjacent the

opposite edge thereof, the members projecting horizontally from the ladder and formed at their outer extremities to provide a depending apertured lug 12. These lugs receive a transverse bar 13 which provides a connection between the rung engaging members 10 as is obvious, the extremities of the rod projecting an appreciable distance beyond the lugs 12 to provide a connection between 65 the various parts of the adjustable supporting means to be hereinafter more fully described. Resting upon the members 10 is a shelf or support 14 which may be constructed from any suitable material and desired 70 dimensions, the shelf being secured to the members 10 in any suitable manner preferably by means of the screw bolts 15.

It is my purpose to provide an adjustable supporting means for the shelf whereby the 75 latter at all times will maintain a horizontal position irrespective of the inclination at which the ladder is supported, and as shown in this instance use is made of a pair of vertically disposed rung engaging members 80 disposed at the opposite sides of the shelf and rising thereabove. Each of these members comprises relatively adjustable sections 16 and 17 respectively, the latter being provided with an eye at its lower end for the 85 reception of the extremities of the transverse bar 13, while the upper end of the section 16 terminates to provide a hook 18 adapted to engage one of the rungs of the ladder at a suitable distance above the shelf 90 14. Each of the sections have the major portion of their length disposed in face to face contact for sliding adjustment relatively, and are embraced by suitable guides 95 19 to hold the sections properly positioned during their adjustment. Each section is also formed at a point in its length with a shoulder 20 forming an abutment for the end of the other section to limit the adjustment of these parts to their normal position. 100 A screw bolt 21 is carried by the section 16 and projects through a longitudinally disposed slot 22 in the section 17, and adjustably associated with the bolt is a thumb nut 23 through the instrumentality of which the 105 sections may be held fixed relatively in adjusted position. It is manifest that when the ladder is supported at the inclination shown in full lines in Fig. 2 the vertically disposed rung engaging members must be 110 shortened to accommodate themselves to the latter to hold the support in horizontal posi-

tion. If the ladder is arranged at the inclination shown by dotted lines in this figure these hook engaging members are in consequence lengthened for the same purpose.

5 Depending from the opposite end of the transverse bar 13 and pivotally associated therewith are auxiliary supporting arms 24 each being provided with a relatively broad extremity 25 adapted to engage the side stiles 10 of the ladder in active position. Embracing the extremities of the transverse bar 13 outwardly of the arms 24 are collars 26 having associated therewith threaded bolts 27 adapted when screwed into engagement with 15 the bar to hold the various parts of the adjustable supporting means fixed in operative position. The arms 24 adjacent their free ends are further supported by means of slotted links 28 depending from the support 20 14 at the opposite sides thereof and pivotally associated therewith. The arms 24 carry threaded bolts 29 which project through the slot 30 of the links 28 for sliding adjustment therein, the bolts providing a connection between the arms 24 and the links 28 whereby 25 these parts are simultaneously adjusted to a position for use, a thumb nut 31 being associated with the bolts through the instrumentality of which the arms and links may 30 be held fixed relatively in their proper adjusted position.

The construction of the device in its entirety is such that the various parts can be easily and quickly adjusted to their proper position at the bottom of the ladder, subsequent to arranging the ladder at its proper inclination for use. The attachment can then be removed and carried by the workman up the ladder to the location desired, 40 whereupon the rung engaging members can be easily hooked over the proper rungs. The adjustment is very simple in construction and when applied to a ladder has an unlimited number of uses and advantages.

45 It is obvious that the vertically disposed rung engaging members are adjustable independently of the supporting elements depending from the support, whereby these various elements can be so positioned to effectually and rigidly maintain the support 50 14 in a true horizontal position irrespective of the inclination at which the ladder is ar-

ranged, and permitting the attachment to be used in safety.

What is claimed is:—

55

1. A ladder attachment comprising a pair of horizontally disposed rung engaging members, a platform resting upon and secured to said members, a transversely disposed rod passed through aligned apertures in the forward extremities of said members, said rod projecting beyond the outer longitudinal edges of said members, arms depending from the extremities of said rod and pivotally connected with the latter, means for holding said arms at a given inclination, said arms having beveled extremities to engage the side stiles of the ladder, and adjustable elements connected with said rod and adapted to engage one of the rungs of the ladder above the platform to hold the latter in a horizontal position irrespective of the inclination of the ladder.

2. A ladder attachment comprising a pair of horizontally disposed rung engaging members, a platform resting upon and secured to said members, the forward extremities of said members being formed to provide bearings, a transversely disposed rod arranged in said bearings and having its 75 extremities projecting beyond the sides of said members, adjustable elements connected with the rod and adapted to engage one of the rungs above the platform to hold the latter in a horizontal position irrespective of 80 the inclination of the ladder, arms depending from the extremities of said rod for swinging movement, means for holding said arms in a given position, said arms having beveled extremities to rest against the side stiles of the ladder, a slotted brace element depending from each side of said platform in close proximity to the ladder and a pin carried by each arm and movable in the slot of the adjacent brace element, whereby said arms and brace elements are adjusted in 85 unison.

90 In testimony whereof I affix my signature in presence of two witnesses.

95 CHARLIE H. POOL.
